31 Claims. (Cl. 219—38)

This invention relates generally to heating devices and in particular to a unit heater of internal combustion type for a mobile craft which is entirely operable independently of the motive engine for such craft.

The prior art vehicle heaters of internal combustion type are of two general classes, namely, suction and pressure heaters. These heaters are generally operable on a relatively high pressure supply air having sufficient velocity and volume to suitably atomize the fuel to be burned and to maintain a positive flow of the combustible and burning mixture through the heater. This air is usually supplied by utilizing a portion of the engine power, either by direct-connected fan or blower means for the pressure heaters, or by connection with the engine intake manifold for the suction heaters. The heaters, therefore, are dependent for their operation upon a concurrent operation of the engine and are directly responsive in operation to engine running conditions rather than to heater operating or vehicle heating conditions. Due to the variation in the air as supplied by the engine, the conditions in the combustion chamber are subject to great variation so that burning within the heater is erratic and of highly varying efficiency. Where carburetors and aspirating means are utilized, the fuel is admitted into the combustion chamber in proportion to the volume of air supplied. A large quantity of fuel is thus fed into the combustion chamber during a period of light load engine operation while a relatively smaller amount of fuel is admitted to the combustion chamber during a period of heavy load operation. Since the engine load is subject to rapid and frequent changing it is readily apparent that the fuel is burned at a very uneven rate. In some instances combustion may be completely stopped by a too sudden change in the quantity of fuel admitted to the combustion chamber. This fluctuation of the air supply and the consequent surging of fuel in the combustion chamber, effects a noisy burning of the fuel which is annoying and disturbing, especially when the heater is located adjacent to, or in the passenger compartment of the vehicle.

Attempts have been made to overcome these disadvantages of the usual suction and pressure vehicle heaters but these attempts have been thwarted at the outset by the fact that the only power available, apart from the engine power, for operating any of the vehicle equipment is the engine battery. Since this battery is of limited capacity, a heater operable therefrom is re-

stricted in its operation to limited or critical operating pressures.

In the case of an automobile which includes the usual battery, generator and other associated electrical equipment, the maximum available current for heater operation is possibly about 7 amperes. It is possible, of course, that a current heavier than 7 amperes might be obtained over some periods of operation, but this heavier current would result in a serious drain on the battery, and in the winter time would seriously interfere with the satisfactory operation and starting of the automobile engine. The operation of an automobile heater entirely from the battery, therefore, requires a complete change in the size and assembly of the parts of the usual suction and pressure heaters to adapt such heaters for operation by the battery. Particularly, the reduction in the size of the air supply means to provide for its electrical operation so reduces its capacity output, as to have heretofore made a battery operated car heater of internal combustion type commercially unavailable.

It is an object of this invention, therefore, to provide an improved vehicle heater of unit type which is operable entirely independently of the vehicle engine.

Another object of this invention is to provide an improved automobile heater of internal combustion type, which is of unit assembly and operable entirely by the power from the usual automobile battery.

A further object of this invention is to provide a heater of internal combustion type for mobile craft which is efficient and quiet in operation and adapted to be mounted remotely from the craft motive engine.

Yet another object of this invention is to provide a heater of internal combustion type which is completely operable in response to heater operating conditions.

A still further object of this invention is to provide a package heater of internal combustion type which is operable entirely from the power in a usual car battery, and which is simple and rugged in construction, small and compact in assembly, and inexpensive to manufacture.

A feature of this invention is found in the provision of a unit heater of internal combustion type which requires only a storage battery and a small capacity fuel tank for its complete and efficient operation.

Another feature of this invention is found in the provision of a unit automobile heater of internal combustion type which includes a combus-

tion compartment and a mechanical compartment within an enclosing housing structure. The air recirculated from the passenger compartment is passed through the mechanical compartment prior to its passage through the combustion compartment, whereby to cool the operating devices in the mechanical compartment.

Another feature of this invention is found in the provision of an automobile unit heater of internal combustion type which is mounted outside of the passenger compartment of the automobile, but which is completely operated by control mechanism located within the passenger compartment and on the automobile dashboard.

Yet another feature of this invention is found in the provision of an automobile heater of internal combustion type which has a substantially constant heat output, the temperature in the passenger compartment of the automobile being controlled by varying the volume of the heated air admitted to the passenger compartment from the heater.

A further feature of this invention is found in the provision of a heater of internal combustion type having a conditioning unit for treating the fuel prior to its ignition which is preassembled before its installation in the heater, whereby to facilitate the assembly and service work on the heater.

Another feature of this invention is found in the provision of an automobile heater of internal combustion type which is operable entirely independently of the automobile engine and enclosed by an integrally formed housing structure. The housing is divided into a mechanical compartment and a combustion compartment, with the mechanical devices being mounted and supported on the dividing wall between the compartments so that ready access is had to all of the mechanical devices immediately on removal of the housing.

Yet a further feature of this invention is found in the provision of a heater of internal combustion type having a fuel conditioning unit including a heating element with an end portion extending from the unit and having thermostatic means mounted thereon. The thermostat is operable in direct response to the temperature condition of the heating element to control its operation whereby to retain the temperature of the heating element substantially constant by the practical elimination of any time lag in such control.

Yet another feature of this invention is found in the provision of a heater of internal combustion type having a fuel system including a pulsating type pump and a fuel nozzle which has a cavity formed therein between the inlet and outlet thereof, the cavity being of a large volume relative to the injector discharge passage whereby to cushion and substantially eliminate any pulsating effects of the pump in the nozzle discharge passage.

A further feature of this invention is found in the provision of a combustion chamber for a heater of internal combustion type which is of substantially cylindrical shape and includes a body and fin portions of integral construction. A partition member engageable with the fins and positioned within the chamber body is of a construction to divide the chamber into a plurality of connected axially extending passages, whereby to provide a chamber of elongated construction.

Another feature of this invention is the provision of a heater of internal combustion type

having a fuel system which includes a pulsating type pump and a device for metering the fuel flow from the pump in a manner to provide for a substantially uniform rate of flow in the system.

5 Further objects, features and advantages of this invention will become apparent from the following description when taken in connection with the accompanying drawings in which:

Fig. 1 is a view in perspective of the complete heater assembly;

Fig. 2 is a detail view in perspective of the partition member for dividing the heater combustion chamber into a plurality of axially extending passages;

Fig. 3 is a sectional view as seen along the line 3—3 in Fig. 1, the showing of the combustion chamber being somewhat of a developed view;

Fig. 4 is a sectional detail view of the fuel conditioning unit illustrated in Fig. 3;

Fig. 4a shows the fuel conditioning unit of Fig. 4 with a modified thermostatic unit;

Fig. 5 is a view as seen along the line 5—5 in Fig. 4;

Fig. 6 is a modified form of the conditioning unit illustrated in Fig. 4;

Fig. 7 is a sectional detail view of the fuel metering device which is shown diagrammatically in Figs. 1 and 3;

Fig. 8 is an end view of the heater unit looking at the fuel conditioning unit, with portions thereof being removed for the purpose of clarity;

Fig. 9 is an end view of the combustion chamber showing the assembly arrangement therein of the dividing member shown in Fig. 2;

Fig. 10 illustrates diagrammatically a control circuit for the heater assembly including the fuel conditioning unit of Fig. 4;

Fig. 11 is illustrated similarly to Fig. 10, but is applicable to the modified fuel conditioning unit shown in Fig. 7;

Fig. 12 is a plan view of the control unit for the heater;

Fig. 13 is a sectional view as seen along the line 13—13 in Fig. 12;

Fig. 14 is an elevational view of the control unit looking toward the right as viewed in Figs. 12 and 13, and

Fig. 15 is a fragmentary side view of an automobile with portions thereof removed to show the mounting of the heater and heater control unit relative to the automobile passenger compartment.

The invention is illustrated as applied to an automobile, the heater unit being completely enclosed and provided with suitable leads for connection of its fuel system with the usual automobile gas tank and connection of its control circuit with the usual car battery. It is contemplated that the heater be entirely operable independently of the automobile engine and operated entirely by the electrical power from the usual car battery. Since the electrical power available from the usual car battery is relatively small the motor in the heater, which is common to the air supply and air recirculating means, is of a size to operate on about 5 amperes of current. This current rating is far below the average amperage rating of the normal car battery and well within all practical factors of safety for heater current consumption. The use of a 5 ampere motor for operating the air and fuel supply means produces an effective operating air pressure in the heater of about $\frac{1}{8}$ " to $\frac{1}{4}$ " of water. Fuel cannot be properly atomized by an air pressure of this order so that the air and fuel

mixed at these pressures forms what is commonly referred to as a "wet" mixture. Before this "wet" mixture can be efficiently burned it must be completely broken up and intimately mixed with the supply air prior to its ignition. This invention, therefore, also provides means for conditioning the fuel prior to its ignition, and means for progressively burning the combustible mixture over substantially the complete length of a combustion chamber of elongated construction. The air from the automobile passenger compartment is circulated directly about the combustion chamber, with the temperature within the compartment being controlled by varying the amount of heated air entering the passenger compartment from the heater.

Referring to Figs. 1 and 3 of the drawings the heater 20 is seen to include a substantially centrally disposed longitudinally extending frame member 21 having a vertically extending wall portion 22 which divides the heater into a mechanical compartment 23 and a combustion compartment 24. Compartment 24 accommodates a combustion chamber 27 which is substantially coextensive in length with the compartment 24 and is secured to one side of the vertical wall 22 between laterally extending wall portions 28. Wall portion 22 is formed with cut or punched out ear portions 29 and 29', which extend substantially normal to the wall and into the mechanical compartment 23.

A fuel pump 31, which may be of solenoid type, is mounted on an ear portion 29'. A fuel metering device, indicated at 32, is in the fuel line 33 which connects the pump with a fuel nozzle 34 mounted in a fuel conditioning unit 36, to be later explained. Operation of the pump is controlled by a breaker assembly 37 which is in operative engagement with the shaft 38 of a motor 39. The motor 39 operates an air supply fan 41 and a recirculated air fan 42, the fans 41 and 42 being mounted on the extended shaft portion 43 which is supported on a frame member 44 having a portion thereof arranged between the fans. It is thus seen that all of the operating devices of the heater are located in the mechanical compartment 23 with the combustion chamber 27 being arranged in the compartment 24, so that the removal of the housing member 30 completely opens the compartment 23 for access to the motor 39, fuel pump 31, metering device 32, and air fans 41 and 42.

Plate 44, as is best seen in Fig. 3, forms part of a passage 46 which extends about the combustion chamber 27. The recirculated air is drawn into the mechanical compartment 23 through an aperture 47 (Fig. 1) formed in a housing member 25, the air from the compartment being discharged by the fan into the passage 46 and outwardly from the unit through the air-header 50 and discharge outlet 48. Supply air for combustion enters the heater through the inlet 67 formed in the housing 30 and is discharged by the fan 41 into an air supply chamber 66, to be explained.

The combustion chamber 27 (Figs. 1 and 9) is of substantially cylindrical shape and includes a body member 27a of unit construction and formed from a single piece of flat sheet steel or suitable like material. The member 27a is press shaped to form a series of alternate peripheral sections 40 and axially extending radial fin elements 45, a fin 45 being arranged between adjacent peripheral sections 40. As is clearly seen in Fig. 9, each fin 45 is bent double so as to have twice the thick-

ness of a peripheral section 40. The outer ends 55 of the fins 45 are thus closed while their inner ends 49 are open and readily separable. Positioned within the body portion 27a is a partition member 52 which is of substantially cross-shape and comprised of dovetailed members 53 and 54 which are of a width substantially equal to the diameter of the combustion chamber 27. As shown in Fig. 2, plate 53 is of substantially rectangular form and slightly less in length than the plate 54. Plate 54 is also of substantially rectangular shape and is formed with a projection 56 at one end thereof which lies to one side of the plane of the plates 53 when the plates 53 and 54 are in their dovetailed engagement.

In arranging the partition member 52 within the body portion 27a, the body portion is formed into a cylinder, the abutting ends being secured together as by welding or like means. The sides 58 of the plate 54 are then positioned in oppositely disposed fins indicated as 45a, while the sides 59 of the plate 53 are positioned in fins 45b, which are angularly displaced approximately 90 degrees from the fins 45a. The plate 54 is substantially coextensive in length with the body portion 27a and upon its being completely extended therethrough, the inner ends 49 of all of the fins are rigidly secured together, as by welding or like means. The member 52 and the body portion 27a are thus assembled into a rigid and integral unit. The chamber 27 is closed at its ends by plates 61 and 62 which are also welded to the body portion 27a.

The partition member 52 is thus seen to provide for a series of connected passages within the body portion 27a which have a combined length of four times that of the body portion 27a. An inlet and an outlet for the elongated passage is obtained by the apertures 63 and 64, respectively, formed in the end plate 62. Thus as indicated by the arrows in Figs. 2 and 3 the continuity of the passage from the inlet 63 is through the quadrants 51a, 51b, 51c and 51d, in that order, and outwardly through the combustion chamber outlet 64. A cylindrical shell or sleeve 65 positioned about the fin ends 55 encloses the body portion 27a to form the annular passage 46, which is divided radially by the fins 45. It is readily apparent that partition members may be readily provided to form a varying number of longitudinal passages in the combustion chamber 27, the size of the chamber 27 and hence the size of the passages being controlling in the number desired.

The inlet 63 of the combustion chamber is of somewhat smaller diameter than the chamber passage 51a and is provided with an inwardly extending flange portion 60 for the mounting thereon of the fuel conditioning unit 36. A part of the unit 36 (Figs. 3 and 4) is located within the air supply chamber 66, which is formed at one end of the combustion chamber 27 by the end plate 62, the partition plate 44 and the housing members 25 and 30. The unit 36 includes an air and fuel mixing chamber 68 and an equalizing chamber 69, which are formed within a housing 71 of substantially cylindrical shape. As viewed in Fig. 4 the upper side of the housing 71 is of substantially straight contour, while the lower side is of substantially stepped contour near the closed housing end 72. The stepped or wall portion 73 is located substantially opposite the air and fuel inlet 74 to the chamber 68. Inlet 74 is formed with a suitable mounting portion for the fuel nozzle 34, which was previously mentioned, the air for combustion being admitted into the

mixing chamber through apertures 75 arranged about the inlet 74.

The nozzle 34 is of substantially cylindrical form and is provided with a body portion 34a having a Venturi passage 77 therein, and a top portion 78. The top portion 78 is provided with a cavity 79 which is connected with the fuel line 33 at the nozzle inlet 81 and is in communication with the venturi 77 through a discharge passage 82. In pumps which operate to produce pulsations in the fuel line, such as the solenoid pump 31, the fuel in the supply line is discharged in waves rather than in a steady or uniform flow. The cavity 79 acts to cushion these fuel surges caused by the pump by virtue of the fact that the air pocket which is formed above the cavity, during normal operation of the fuel system, is compressed to absorb the fuel pulsations. To provide for the greatest uniformity in the rate of fuel flow, the volume of the cavity 79 is rather large relative to the volume of the discharge passage 82. In one commercial embodiment of the invention the cavity has a volume of about .061 cubic inch while the volume of the discharge passage is .000119 cubic inch. In this embodiment the diameter of the passage is about .02 of an inch and the length about $\frac{1}{8}$ of an inch, the small diameter opening serving further to cushion the fuel pulsations caused by the pump 31. This construction of the nozzle 34 serves to reduce the pump pulsating effects in the discharge passage to a minimum so that the fuel flow in the passage 82 and through the venturi 77 is substantially steady and even.

The quantity of fuel passing through the nozzle 34 and hence admitted to the unit 36, is regulated by the fuel metering device 32, which is shown in detail in Fig. 7. A body member 83 of sleeve form is threadably connected at one end to the pump 31, a plug 84 being threadably secured to the opposite end thereof for connection with the fuel supply line 33. The body member 83 is of a length to provide for the formation therein between the pump 31 and the plug 84 of a cavity 86 which is filled with a fuel filter of felt or other suitable like material. An air dome or cap 85 is threadably secured in the member 83 in fluid communication with the cavity 86. Dome 85 serves to cushion or absorb any fuel surges in the cavity 86, in a well known manner, so as to effect a more even flow of the fuel through the device 32. The fuel line 33 between the metering element 32 and the nozzle 34 is of a length of about 9 inches. Extended over approximately $\frac{2}{3}$ of this length and in the line 33 is a core member 87 which may be provided in wool yarn, glass, wire or the like. The member 87 functions to meter the fuel by virtue of its increasing the resistance to the flow of the fuel in the line 33 and effecting somewhat of a capillary or surface-tension action between the surfaces of the core member 87 and the fuel pipe or line 33. This action provides for a definite creeping of the fuel through the metering device irrespective of any applied pump pressure; the pump pressure serving to accelerate this creeping action. Increasing the diameter of the core member decreases the fuel flow through the line, but increases the capillary flow of the fuel by virtue of the increase in the surface of the core member. Thus it has been found that a glass core comprised of a plurality of fine strands produces a greater flow by surface action or tension than a single strand of the same diameter. The same general relation was also found to be true in the case of copper wire. It is thus readily apparent

that a variation in both the diameter and the length of the core member 87 relative to the fuel line 33 effects a corresponding variation in the metering of the fuel to the mixing chamber 68 of the conditioning unit 36. However, the rate of fuel flow as effected by the surface tension or capillary characteristics also varies as between the different materials which might be used for the core 87, so that a relatively wide range of metering can be obtained by the metering device 32. It is to be noted also that the restricted fuel line in the metering device serves further to decrease the pulsating effects of the pump 31 in that portion of the fuel line between the metering device and the unit 36.

The mixing chamber 68 and the equalizing chamber 69 are separated from each other by a cup-shaped member 88 which is arranged in the unit housing 71, the closed end 89 of the cup member being positioned near the stepped wall portion 73. The closed end or partition wall 89, is formed over about its upper $\frac{2}{3}$ portion with a plurality of apertures 91, the lower third of the partition being imperforate so that communication between the chambers 68 and 69 is only through the apertures 91. The inclined wall 73 is directed away from the partition wall 89 to form a trough or pocket 92 at the bottom of the unit 36, as viewed in Fig. 4, between the wall 73 and the imperforate bottom portion of the partition 89, for a purpose to be later explained. The open end of the cup member 88 is in abutting engagement with a heat insulating plate 93, which is positioned over the outlet 76, but within the unit 36. An annular rim or flange 94 thus projects outwardly from the unit 36 beyond the plate 93.

As shown in Fig. 5 the plate 93 is formed with a plurality of apertures 96 which are arranged in substantially a complete circle near its peripheral edge. A heating element 97 is mounted in the plate 93 near the upper portion thereof. The element 97 is of substantially cylindrical shape and extends axially outwardly from the unit 36, and is formed at its free end with an enlarged heating portion 98. The element 97 functions as a hot spot to continue the burning of an already ignited mixture, as will be later explained.

It is contemplated in the present invention that the ignition means for the combustible mixture be included as part of a combination preheating and igniting element or unit 99, which comprises a resistance coil 101 arranged in an insulating tube 102, which in turn is mounted in a copper tubular sleeve 103. The element 99 extends longitudinally through the conditioning unit 36, one end 104 thereof extending outwardly from the outlet 76 and an opposite end 105 extending outwardly from the closed end 72 of the unit housing 71. Support of the heating element in the unit is accomplished by its extension through the plates 89 and 93 and the closed housing end 72, with the housing end and the partition wall 89 being arranged in thermal relation therewith. That portion of the heating element in the chambers 68 and 69 functions to heat the fuel conditioning unit 36, the unit housing 71 and the cup member 88 being provided in copper or other high heat conducting material to assure a rapid and uniform distribution of the heat throughout the unit. The chamber 69, which is defined by the partition walls 89 and 93, is filled with a copper wool or like material having high heat conducting characteristics so that the heat from the heating element 99 is conducted into all portions

of the chamber 69. The mixture entering the equalizing chamber 69 is thus continuously heated during its passage therethrough, as will be explained. The element 99, therefore, does not operate as a "hot spot," but operates rather to heat the mixing and equalizing chambers and their surrounding walls to a substantially uniform temperature, with the variation of the temperature within the chambers and their surrounding walls and element 99, being about 10 degrees Fahrenheit.

A controlled heating of the unit 36 for advantageously conditioning or vaporizing the fuel therein is accomplished by means of a thermal switch unit 106 (Fig. 4) which is responsive to the heat of the heating element 99 and acts in part to regulate the operation of such heating means. The unit 106 is mounted on, but electrically insulated from, the heating element end 105 and in its normal assembly within the heater 20 extends into the air supply chamber 66 (Fig. 3). The unit is comprised of bi-metal contact arms 107 and 108 and associated spring contact arms 109 and 110, respectively. As shown in Fig. 8, the arms 107-110, inclusive, are of substantially flat form and are apertured, as at 111, (Fig. 4) so as to be mounted about an insulated clamping sleeve 114, suitable collars 113 of insulating material being arranged between the arms for spacing purposes. The sleeve 114 with the arms 107-110 and spacing collars 113 thereon is then mounted as a unit on the insulating sleeve 12 which in turn is mounted on the heating element 99, as is clearly indicated in Fig. 4. The bi-metal arms 107 and 108 are movable independently of each other and are adapted for movement at different temperatures, bi-metal switch 108-110 being in a normally closed position and arranged in the electrical circuit of the heating element 99, and the bi-metal switch 107-109 being normally open and arranged in the electrical circuit of the fuel pump 31.

Included with the thermostatic unit 106 and adjacent the contact arm 109 is a bracket member 116 having an angular end portion 117. The spring conductor 120 electrically connecting bi-metal arm 108 with the heating element 99 is attached to the element end 105 by a nut 120a to maintain the assembly 106 in position on the element; the tension in the conductor acting to continuously urge the unit 106 against the shoulder portion 125. The bracket member 116 is adapted for engagement with the plate frame portion 44 (Fig. 3) to hold the unit 36 in its assembled position in the heater. The unit 36 is also retained in its assembly position in the heater structure by a spring bracket 118 (Figs. 3 and 4) which is attached to the frame plate 44 and arranged to frictionally engage the knob 119 formed on the portion 78 of the nozzle 34. It is to be noted that the nozzle is also held in its supported position in the unit 36 by the spring bracket 118.

A modified form of the thermostatic unit 106 for the fuel conditioning unit 36 is shown in Fig. 4a. The unit 106' includes a single bi-metallic arm B having contacts C and C' arranged on opposite sides thereof for engagement with contact arms 109' and 110' respectively. Contact arm 109' is arranged in the electrical circuit of the pump 31 and motor 39 and is normally separated from the contact C on bi-metal arm B. The arm 110' forms part of the circuit for the heater 99 and normally is in contact with

contact C' of the arm B, and suitably tensioned to follow the arm B during a part of its movement toward arm 109', as will be explained. The mounting of the unit 106' on the heater 99 is similar in all respects to that of the unit 106. A bracket 117' of substantially right angle shape is arranged adjacent the contact arm 109', with the end portion 117a thereof being suitably recessed to straddle the supporting rim 74' for the fuel nozzle 34. This arrangement of the bracket 117' serves to eliminate any tendency of the unit 106' to rotate about the heating element 99. The unit 36 for either of the thermostatic units 106 or 106' is thus seen to be completely preassembled prior to its installation in the heater 20. This assembly of the liquid fuel conditioner as a unit facilitates its mounting in the heater and makes it entirely and easily accessible for any service work.

In the assembly of the unit 36 in the heater 20 the end 104 of the heating element is located at the combustion chamber inlet 63, the projection of heat from this end acting to ignite the fuel mixture entering the chamber. The heat thus projected is confined at the end 104 by the heat insulating partition 93, the degree of ignition heat being determined essentially by the watt input to the resistance 101 and being contemplated in the present invention to be about 1800° F. The temperature in the mixing and equalizing chamber, however, is at all times less than that which would effect an ignition or burning of the fuel within such chambers, and is contemplated to be about 300° F. Thus although the ignition temperature of the fuel is about 1800° F., the partition 93 substantially prevents this high heat from being transferred into the chambers of the fuel conditioning unit 36, so that an 1800° F. temperature on one side of the plate 93 occurs simultaneously with a temperature of only 300° F. on the opposite side thereof. This large difference between the optimum temperature within the vaporizing or fuel conditioning unit 36 and the ignition temperature within the combustion chamber 27 positively eliminates any burning of the fuel within the conditioning unit 36.

The heating element 99 is energized by its connection with a suitable electrical source such as 50 the car battery 115 (Fig. 10), the circuit from the battery including conductor 121, a main control switch 122, conductors 123 and 124, bi-metal switch 108-110 and conductor 120; the circuit being completed to ground by connection of the 55 resistance wire 101 to the copper tubing 103 at the igniter end 104 of the heating element. Conductors 121 and 123 and control switch 122 are also common to the circuit of the fuel pump 31, which further includes bi-metal switch 107-109, conductor 127, the breaker assembly 37 and a conductor 128. The motor 39 is connected directly to the battery 115 through conductors 121 and 123, and the control switch 122.

Operation of the heater 20 is started by closing 65 the main switch 122 which simultaneously operates the heating element 99 and fans 41 and 42, the circuit of the fuel pump 31 being opened by the normally open bi-metal switch 107-109 (Fig. 10). When the heating element 99 is heated to 70 a temperature of about 75° F., the bi-metal arm 107 moves into contact with the arm 109 to close the circuit of the fuel pump 31. The pump circuit is thus closed only when the element 99 is in an operable condition. The air and fuel supplied to the chamber 68 by the fan 41 and fuel

pump 31 contacts the inclined wall portion 73 and that portion of the heater element 99 within the chamber 68. Since the wall 73 is at substantially the same temperature as the heating element 99, the fuel is partially vaporized by such contact so as to be intimately and thoroughly mixed with the air. The resultant mixture is forced through the apertures 91 in the partition wall 89 and then into the equalizing chamber 69 by the effective operating pressure produced in the air supply chamber 66 by the air supply fan 41. The mixture from the equalizing chamber passes through the apertures 96 in the insulating plate partition 93 into the combustion chamber 27, where it is ignited by the hot end 104 of the heating element 99.

After combustion has been thus started the continued operation of the heater 20 and heater element 99 serves to increase the temperature of the element 99 and hence of the chambers 68 and 69. When the temperature of the element heating portion reaches a value of about 200° F., which represents a minimum operating temperature for advantageously conditioning the air and fuel for efficient combustion at low pressures, the bi-metal arm 108 moves out of contact with the arm 110 to stop the operation of the heating element; the fans 41 and 42 and fuel pump 31 continuing in operation. Since the variation of the temperatures between the chambers 68 and 69, and the heating element 99, as was previously mentioned, is only about 10° F., it is to be understood that this optimum temperature is also substantially the temperature of the chambers. However, since the thermostat 106 is responsive directly to the temperature condition of the heating element, the element only will be referred to in the following description. At this operating temperature of 200° F., the fuel contacting the element 99 and the wall portion 73 is substantially immediately vaporized by the heat in these parts, the angular inclination of the wall 73 deflecting the mixture against the partition wall 89 to substantially completely vaporize all of the fuel supplied to the chamber 68. Any raw or free fuel particles which are not immediately vaporized in this manner drop to the bottom of the chamber 68 and into the fuel cavity or trough 92. Since the cavity is formed by the heated wall 73 and partition 89 and further has the heating element 99 extending across the top thereof, the raw fuel thus collected is additionally heated. The collected fuel is also exposed to the warm supply air circulating within the chamber 68 whereby to facilitate its passage into the chamber 69 in a vaporous form. All unmixed or free fuel particles are thus retained in the chamber 68 until they are properly conditioned so that all of the fuel passing into the chamber 69 is in a vaporous form.

The vaporous form of the mixture is maintained in the chamber 69 by virtue of the heated copper wool in the chamber, the wool acting further to diffuse all portions of the mixture to produce a mixture of substantially uniform fuel density. Since the mixture in the chamber 68 is in somewhat of a turbulent state, the structure of the chamber 69 acts further to equalize the velocity flow and pressure of the mixture over the entire transverse cross-sectional area thereof. The fuel mixture entering the chamber 27 through the apertures 96 in the insulating plate 93 is thus of substantially uniform consistency and is free of any isolated rich or lean fuel por-

tions, so that burning of the fuel proceeds both quietly and efficiently.

The above described operating condition of the heater continues until the temperature of the heating portion of the element 99 falls below about 200° F., at which temperature the bimetal arm 108 moves into contact with the arm 110 to again energize the heating element 99. When the temperature of the heating element and hence of the chamber 68 is again increased to about 200° F., the bi-metal arm 108 breaks away from the contact arm 110 to again open the circuit of the heating element 99. This controlled operation of the unit 36 continues during normal operation of the heater, which operation is stopped by opening the switch 122.

During the normal operation of the heater a portion of the heat from the combustion chamber 27 is transmitted through the walls of the fuel conditioning unit 36 and also through the heater element 99 to the mixing chamber 68 and equalizing chamber 69. This transfer of heat decreases the dissipation of heat from these chambers, and particularly that loss of heat which occurs in the chamber 68 by virtue of the vaporization of the fuel therein. In this manner the conducted heat functions as a saving device to reduce a frequent and prolonged operation of the bi-metal switch 108-110 in its control of the heating element 99.

The location of the thermal unit 106 on the element end 105 substantially eliminates any drifting of the temperature in the mixing chamber. This desired condition is accomplished because the thermal unit is in substantially direct thermal connection with the heating element and operates substantially immediately to control the heater element. The time lag between the response of the unit 106 to the temperature condition of the element 99 and its control of the operation of the element is thus reduced to a minimum so that a practically uniform operating temperature occurs in the mixing and equalizing chambers. It is to be understood, however, that the energization of the heating element 99 by the thermal unit 106 does not indicate any failure of combustion in the chamber 27. The fuel is processed or conditioned entirely independently of the burning conditions in the combustion chamber 27 and the bi-metal switch 106 operates to energize the heating element only in response to the temperature conditions in the mixing chamber 68, which as previously mentioned, is of substantially the same temperature as the heating element.

The mixture from the mixing chamber 68 is retained in a vaporous form for burning in the combustion chamber 27 by virtue of the heat transmitted thereto from the wool in the chamber 69. However, in the passage of any flame or spark from the combustion chamber into the equalizing chamber 69, the relative temperature difference between the combustion chamber and the equalizing chamber is such that heat is taken up by the copper wool so that the flame or spark is extinguished by the reduction of its temperature below the ignition point of the mixture. The equalizing chamber 69 thus acts to prevent any occurrence of flashback in the combustion chamber 27 from entering the mixing chamber 68.

To assure a positive and immediate burning of the fuel at all times of heater operation, it is contemplated that the air and fuel be supplied to the mixing chamber 68 in relative proportions to provide a mixture rich in fuel. Although a

rich mixture is readily ignited it is inefficiently burned unless additional air is mixed with the rich fuel portions remaining after the initial ignition of the mixture. A portion of this additional air is admitted into the combustion chamber directly from the air supply chamber 66 through apertures 63a formed in the end plate 62 and about the combustion chamber inlet 63 (Figs. 3 and 8). Since the air in the supply chamber 66 is under the pressure of the fan 41, it is readily apparent that the air moves through the apertures 63a with an initial velocity. By virtue of the rim portion 94 at the fuel conditioning outlet 76, the air flow through the apertures 63a is kept away from the mixture leaving the unit 36, until after ignition thereof. The initially rich mixture is thus first ignited prior to the addition thereto of additional free air.

The air from the ports 63a, however, does not provide for a complete burning of the mixture. Because of the elongated construction of the combustion chamber and the low velocity of the air at the ports 75 and 63a, a progressive burning of the mixture serves to move the flame and mixture through the chamber 27. As this burning mixture passes along the hot spot 97, the heat therefrom acts to immediately intensify the burning of the mixture so that a hot blue flame is projected through the center of the chamber passage to progressively mix with and burn the rich fuel mixture extending thereabout. This progressive burning of the initially rich fuel mixture is facilitated by admitting additional air into the passage 51c through the port 62a, which also opens into the air supply chamber 66. A tube T at the aperture 62a extends within the quadrant 51c a distance at least beyond the communicating passage between quadrants 51b and 51c to direct the flow of the air therethrough only into the quadrant 51c. It is thus seen that a hot flame through the chamber 27 coacts with additional or supplementary air to progressively burn to completion an initially rich fuel mixture, the burning being extended over substantially the entire length of the combustion chamber.

The heating element or hot spot 97 by virtue of the loose terminology applicable thereto may be referred to as a reigniter. However, in function, one theory propounded is that the element 97 gasifies the originally vaporous fuel mixture which passes adjacent thereto and that this gasification increases its rate of burning and effects an expansion thereof which acts to accelerate the flow of the mixture through the chamber 27. Gasification of the vaporous mixture then proceeds progressively, additional air being added to assure sufficient air for an efficient and complete burning of the mixture.

A final portion of air is admitted into the combustion chamber through a tube 64a, which is mounted in the end plate 62 and extends into the passage 51d. Tube 64a is in communication with the supply chamber 66; the extending end 64b being of hook shape and bent in the direction of mixture flow.

It is contemplated that the tube extend about three inches into the passage 51d, which is about ten inches long. This short tube length permits but little space for any additional burning of the mixture, the primary function of the air from the tube 64a being to cool the exhaust gases whereby to reduce the back pressures in the passages 51a-51d, which are of relatively small section. It is to be noted that the air through the apertures 63, tube T and tube 64a

is directed in the direction of mixture flow to aid the flow through the chamber 27.

The operation of the heater utilizing the thermostatic unit 106' is more clearly understood with reference to Fig. 4a and in particular to the control circuit which is diagrammatically illustrated therein. Closing of the main switch 201 closes the energizing circuit for the heating element which from the battery 115 includes conductor 202, bi-metal arm B, contact arm 110', resistance coil 101 and ground connection 203. When the bi-metal arm B is heated to about 80° F. by the element 99 it moves into contact with the arm 109' whereby to energize the circuits for the pump 31 and motor 39. The pump circuit is comprised of conductor 202, arms B and 109', conductor 204, breaker assembly 31 and ground connection 206, the motor being connected to the conductor 204 and grounded at 207. The arm 110' is normally tensioned to follow the bi-metal arm B until the heater element 99 and hence chamber 68 reaches a temperature of about 200° F. At this time contact C' breaks away from arm 110' whereby to open the heater circuit, the pump 31 and motor 39 continuing in operation. Should the temperature of the chamber 68 fall below about 200° F. bi-metal arm B will remake contact with arm 110' to again energize the heater 99. If for any reason, such as a failure of the heating element 99 to become heated, the temperature of the chamber 68 after closing of the heater circuit should continue to decrease, bi-metal arm B will continue its movement toward the right, as viewed in Fig. 4a, until contact with arm 109' is broken, thereby stopping the operation of the pump 31 and fan 39. Air and fuel is thus supplied to the unit 36 only when the heating unit 99 is in an operable condition. Under normal operating conditions, however, the bi-metal arm B is in contact with both arms 109' and 110' for a temperature range of the chamber 68 of from about 80° F. to 200° F. In view of the foregoing detailed description of the heater operation with reference to Figs. 4 and 10 its complete operation with the thermostatic unit 106' is believed to be entirely clear from the above description of the circuit diagram in Fig. 4a.

A modified form of the fuel conditioning unit 36 shown in Fig. 4, is illustrated in Fig. 6, a heating element 99' and an igniter element 104', being indicated as physically independent. Since the remainder of the unit 36' is substantially similar in construction to the unit 36, similar numerals of reference shall be used to designate similar parts. The element 99' is supported in the wall 89 and closed end of the unit housing 71, the assembly of the thermostat 106 and nozzle 34 (not shown) relative to the element 99' being identical with the assembly of Fig. 4. Heat insulating plate 93' is formed with peripherally extending apertures 95', the element 99' extending only through the chambers 68 and 69 and not being supported in the plate 93'. The heat generated by the element 99' is, therefore, utilized entirely in heating the conditioning unit chambers 68 and 69. Although the heater element 99' is thermally connected with the housing 71 and member 88 it is electrically insulated therefrom so that the copper tubing 103' may be utilized as an electrical conductor, as will be explained. Igniter 104' is located within the passage 51a of the combustion chamber 27 in a position relative to the outlet 76 of the unit 36' and to the end 98 of the heating element 97.

which is substantially the same as that of the end 104 of the combined heating and igniting element 99 of Fig. 4.

An operating circuit for the heater 20 utilizing the conditioning unit 36' of Fig. 6, is shown in Fig. 11. The element 99' is electrically connected with the car battery 115, the operating circuit from the battery including conductor 121, main control switch 122, and conductor 131 which is connected directly to the resistance coil 101' of the element. Since the coil 101' is connected directly to the copper tubing 103' the tubing is used as a conductor for connecting the coil 101' with the bi-metal switch 108-110. The circuit is completed by connection of the switch 108-110 through conductor 132 with the igniter 104' which is grounded at 133. It is thus seen that the heating element 99' and igniter 104' are connected in series so as to be operable concurrently on closing of the bi-metal switch 108-110. The motor 39 is connected directly to the battery 115 through conductors 121 and 123 and the control switch 122. The motor circuit is also common to the circuit of the fuel pump 31 which includes further conductor 134, breaker assembly 37, conductor 136, and the bi-metal switch 107-109. On closing of the main switch 122, the heating element 99' and igniter 104' are energized simultaneously similarly to the energization of the entire heating element 99. In one commercial embodiment of this structure it is contemplated that #19 wire be used in the heating element 99', and #20 wire in the igniter 104'. The igniter will thus heat up to a higher temperature than the heating element. Since the remainder of the control circuit and the operation the thermostatic unit 106 is identical in all respects with the operation of the control circuit and operation of the heater 20 previously described in connection with Fig. 10, a further description of the operation of the circuit of Fig. 11 is believed to be unnecessary.

One commercial arrangement of the heater 20 showing its application to the heating of an automobile is illustrated in Fig. 15, the heater 20 being shown as mounted below the automobile passenger compartment 137 and under the front seat 138 therein. The recirculated air inlet 47 and outlet 48 are located on opposite sides of a baffle directing plate 139 to eliminate any short circuiting of the recirculated air between the openings 47 and 48 and to provide for a circulation of the air to all portions of the passenger compartment, as indicated by the arrows.

Operating control of the heater is accomplished by a control unit 141 which includes the main switch 122 of the heater control circuit. The control unit is provided with a housing 142 of box shape, mounted on the dashboard 143 and having a front wall 144 of arcuate contour formed with a laterally extending slot 146 therein. (Figs. 12 and 14). A control lever 147 of substantially T-shape is pivotally supported at 148 intermediate the ends of its cross-member 149. The end 151 of cross-member 149 is directly engageable with the control switch 122, which is of knife-switch type, the contacts 153 and 154 thereof being normally tensioned for contact engagement. Movement, therefore, of the arm end between the switch blades breaks engagement between the contacts whereby to open the switch and to stop operation of the heater. This control of the switch is accomplished by manipulation of the lever about its pivotal support 148 and in the slot 146.

The end 156 of the cross member 149 is operatively connected, as by a Bowden wire 157 to a bypass valve 158 (Figs. 1, 3, and 15), which is mounted on the housing member 30. The valve 5 includes a body portion 161 of substantially bell shape, which is secured at its open end to the member 30 and is formed in the sides thereof with vents 162. The wire 157 is slidably supported centrally of the valve housing 161 and 10 is connected to a cup-shaped valve portion 163 which covers an aperture 164 formed in member 30. The valve 163 is operated in an obvious manner by slidable movement of the wire within the housing 161, whereby to move the valve portion 15 163 relative to the opening 164. This slidable movement of the wire is also accomplished by manipulation of the control lever 147 about its pivotal support and in the slot 146.

With the lever 147 in the full line position indicated in Fig. 12, the valve 163 is in the closed position shown in Fig. 3, and the switch at the open position shown best in Fig. 13. By suitable indicia 165 (Fig. 14) positioned above the slot 146, it is seen that this full line position of the 25 lever represents the "off" condition of the heater. On initial movement of the lever to its dotted line position, shown in Fig. 12, or to the right as viewed in Fig. 14, the arm end 151 is withdrawn from its engagement with the switch 122 to permit closing of the contact arms 153 and 154 and a consequent operation of the heater. This starting position of heater operation designates the maximum volume of heated air which is supplied to the automobile compartment 137, 30 as indicated on the indicia 166. On a continued moving of the lever 147, the switch 122 remains unaffected, but movement of the arm end 156 draws on the wire 157 to move the valve portion 163 progressively farther away from the opening 164 in the housing member 30. The heated air from the header portion 50, which would normally pass through the heater outlet 48 into the compartment 137, is thus by-passed through the opening 164 and vents 162 to the atmosphere. In this manner the amount of heated air supplied 45 to the compartment is reduced, it being apparent that a fresh air makeup for the by-passed air is readily obtained by opening the usual car window. The header 50 is also connected by a conduit 168 with a defroster unit 171. As illustrated in Figs. 3 and 15, the defroster is in continuous 50 operation with operation of the heater.

The invention thus provides for a vehicle heater of unit type which is completely preassembled 55 prior to its mounting on the vehicle and which may be mounted in a plurality of positions adjacent the body compartment of the vehicle. The heater is of rugged and simple construction, small and compact in size, and efficiently operated on the power available from the usual vehicle battery, which is primarily adapted for use in conjunction with the vehicle motive engine. The invention provides further means for conditioning the fuel prior to its ignition in the heater 60 so as to provide for a quiet and steady burning of the mixture in the combustion chamber. The chamber is of substantially cylindrical form and of relatively short length, but is constructed in a manner to have therein a plurality of connected longitudinally extending passages, with combustion 65 of the mixture therein being progressive throughout the combined length of such passages. This retention of an active flame within a combustion chamber of elongated construction provides for a relatively large heat radiatin: sur-

face immediately adjacent the combustion chamber so that the generated heat is utilized directly at its source. The volume of heated air admitted into the passenger compartment from the heater is readily varied by a control unit located for manual operation in the passenger compartment. The division of the heater unit into a mechanical compartment and into a combustion compartment provides further for a distinct isolation of the operating devices from the heat of the combustion chamber, and the utilization of the mechanical compartment as a part of the passage flow for the recirculated air through the heater unit, whereby to effect a continuous cooling of the mechanical devices during all times of heater operation.

It is to be understood that the relative temperature values used in the above description are representative for one kind of fuel and will vary for different kinds of fuel. Although only a preferred embodiment of the invention has been illustrated and described herein, it is to be understood also that the invention is not to be so limited, since alterations and modifications therein can be made which are within the full intended scope of the invention as defined by the appended claims.

I claim:

1. In a unit heater of internal combustion type for mobile craft having a battery and a space to be heated, the combination of a combustion chamber, an air circulating passage about said combustion chamber connected at each end with said space, a by-pass valve in said passage opening to the atmosphere, electrical means for circulating air through said air passage, electrical means for supplying air and fuel to said combustion chamber, ignition means in said combustion chamber, means including an electrical heating element for conditioning the air and fuel prior to its ignition in said combustion chamber, and means in said space operatively connected with said by-pass valve to control the amount of air circulated into the space from about said combustion chamber, with said two electrical means, and the heating element and the ignition means being operated entirely by the electrical power from said battery.

2. In a mobile craft having a space therein and an engine with a battery therefor, a unit heater of internal combustion type having frame means and including in combination a combustion chamber, means for circulating air from said passenger compartment about said combustion chamber, a fuel conditioning unit in operative association with said combustion chamber, a fuel supply, an electrically operated fuel pump for delivering fuel to said conditioning unit from said fuel supply, means for supplying air to said conditioning unit, an electrical motor common to said air circulating and said air supply means, electrical heating means in said conditioning unit, with all of said defined means of said unit heater being operatively supported entirely on said frame means, and housing means for completely enclosing said unit heater, with all of said electrical means being operated by the electrical power from said battery.

3. A heater of internal combustion type for a mobile craft having a space therein, including in combination frame means and an enclosing housing therefor, with said frame means including a wall portion dividing said housing into two compartments, a combustion chamber in one of said compartments, ignition means in said com-

bustion chamber, means for supplying air to said combustion chamber, means for supplying fuel to said combustion chamber, means for conditioning said air and fuel prior to its ignition in said combustion chamber, with said conditioning means being arranged in said one compartment, means for circulating air from said space about said combustion chamber, an electrical motor for operating said air circulating and air supply means, with said motor, air supply means, circulating air means, and fuel supply means being located in the other of said compartments, the recirculated air from the space being passed through said other compartment prior to its circulation about said combustion chamber.

4. A unit heater of internal combustion type for a mobile craft having a space therein, including in combination frame means having a wall portion, housing means for said frame means, said housing means being divided into two compartments by said wall portion, a combustion chamber secured to one side of said wall portion and arranged in one of said compartments, means for supplying air to said combustion chamber, means for supplying fuel to said combustion chamber, said fuel supply means being supported on the opposite side of said wall portion and located within the other of said compartments, means for conditioning said air and fuel prior to its passage into said combustion chamber, said conditioning means being arranged in said one compartment, means for circulating air from said passenger compartment about said combustion chamber, a motor common to said air circulating and said air supply means mounted on the opposite side of said wall portion and within said other compartment, with said circulating air and air supply means being arranged in said one compartment but in fluid flow communication with said other compartment, the circulated air from said space being passed through said other compartment prior to its circulation about the combustion chamber.

5. In a vehicle having a passenger compartment, the combination of a unit heater of internal combustion type mounted below said compartment, and including a combustion chamber, means for supplying air and fuel to said combustion chamber, housing means completely enclosing said unit, an air passage about said combustion chamber, means for connecting said air passage at each end with said passenger compartment, means entirely within said housing means for circulating air through said air passage, means on said housing means for by-passing to the atmosphere a portion of the air passing through said air passage, and means located within said passenger compartment and operatively connected with said air by-pass means to regulate the amount of air entering the passenger compartment from said housing means.

6. In a vehicle having a passenger compartment and a battery, the combination with a unit heater of internal combustion type mounted below said compartment and including a combustion chamber, of a control circuit for said heater including said battery and a normally open main switch, means for circulating air from said compartment about said combustion chamber, means for by-passing a portion of said circulated air to the atmosphere, means including a movable control arm for regulating said by-pass means to control the amount of circulated air passed into said compartment, said control arm being located in said compartment and

having a pair of oppositely extending lateral portions, said two portions being concurrently movable on movement of said control arm, means for operatively connecting one of said portions with said by-pass means, the other of said portions being engageable with said main switch to directly control its operation, with movement of said control arm in one direction moving said other portion to close said switch and the continued movement of the control arm in said one direction moving said one portion to progressively reduce the amount of air which is by-passed from said heater.

7. In an automobile having a passenger compartment and a battery, the combination with a unit heater of internal combustion type operable entirely by the power from said battery and including a combustion chamber, of means including an operating lever for controlling the operation of said heater, said control means being located in said passenger compartment, a control circuit for said heater including said battery, means in said heater for circulating air from said passenger compartment about said combustion chamber, means for by-passing a portion of said circulated air from said heater to the atmosphere, a housing for said control means having a slot in a wall portion thereof, means movably supporting one end of said operating lever in said housing, the opposite end of said lever extending through said slot and being slidably movable therein, said operating lever having oppositely extending arms near said one end, a control switch in said control circuit mounted in said housing, means operatively connecting one of said arms with said by-pass means, the second arm being engageable with said control switch, with moving of said lever to one end of said slot moving said second arm to open said control switch and said one arm to open wide said by-pass means, the movement of said lever toward the opposite end of the slot providing for a gradual decrease in the amount of recirculated air by-passed from said heater, the control switch being open only when the regulating lever is at said one end of the slot.

8. In a heater of internal combustion type, the combination with an air and fuel mixing chamber of a fuel system for supplying fuel to said chamber including a pump having a pulsating discharge, a fuel injector mounted on said chamber and having a discharge passage in fluid flow communication with said chamber and a fuel inlet, said discharge passage having a small diameter with reference to its length and said inlet being in fluid communication with said pump, said injector having a cavity fuel reservoir therein between said discharge passage and inlet, with said reservoir being of a large volume relative to the volume of said discharge passage, said reservoir on operation of said fuel system having an air pocket therein which serves to cushion the discharge pulsations from said pump to provide for a substantially steady flow of fuel from said discharge passage into said chamber.

9. In a heater of internal combustion type, a combustion chamber having a body portion of substantially tubular shape, said body portion being integrally formed with angularly spaced fins extending radially from the periphery thereof, said fins being bent double with their inner ends opening into said chamber, a longitudinally extending partition member of substantially X-shape having end portions, said partition member being fitted within said body portion

with corresponding opposite sides thereof arranged in the inner ends of corresponding oppositely disposed fins, and a cover portion for each end of the body portion, said end portions being open to provide for a continuous circuitous passage in said combustion chamber, with one of said cover portions having an aperture in register with said passage to provide an inlet thereto and an aperture in register with said passage to provide an outlet therefrom.

10. In a heater of internal combustion type, a combustion chamber having a body member of substantially tubular shape with an axial bore therein, said body being of integral construction and having the periphery thereof alternately formed with arcuate portions and longitudinally extending radial fin elements, said fin elements being bent double and having their inner ends opening into said body member, means for dividing the bore of the body member into a plurality of interconnected axially extending passages including a partition member positioned within said bore and extending axially of said body member, with the side portions of said partition member being positioned within the inner ends of certain of said fin elements to retain the partition member fixed relative to said body member, and a cover portion for each end of said body member, with at least one of said cover portions having apertures therein in communication with said interconnected passages.

11. In a heater of internal combustion type, the combination of an air and fuel mixing chamber and a combustion chamber having an inlet, said mixing chamber having an outlet arranged within said inlet, a plate extending over said outlet for insulating the mixing chamber from the heat of the combustion chamber, means for supplying air and fuel to said mixing chamber, a heating element arranged in said mixing chamber for vaporizing the fuel supplied thereto, said heating element having an igniting end portion extending through said heat insulating plate into said combustion chamber, a second heating element mounted in said plate and extending into said combustion chamber, said second heating element being of substantially cylindrical form and having a free end of enlarged section, said enlarged section being arranged in substantial adjacency to said igniting end portion, with said plate having apertures formed near the peripheral portion thereof for admitting the air and fuel mixture from said mixing chamber into the combustion chamber and into the effective heating zones of said igniting end portion and second heating element, and means for adding supplementary air to said mixture after its passage about said second heating element.

12. In a heat generator of internal combustion type, the combination of a combustion chamber having an inlet and an outlet, an air and fuel mixing unit having an outlet arranged within the inlet of said combustion chamber, a heat insulating plate extending over said unit outlet but spaced inwardly therefrom to provide an axially extending annular rim at said outlet, said plate having apertures formed near the peripheral edge thereof, ignition means in said combustion chamber positioned substantially adjacent said annular rim, means for supplying air and fuel to said mixing unit, with the air and fuel mixture initially entering said combustion chamber from said unit being relatively rich, means for supplying secondary air at said combustion chamber inlet and about said rim, said rim re-

taining the secondary air away from the initially rich mixture entering the combustion chamber until substantially immediately after its ignition, means for supplying supplementary air to said combustion chamber intermediate the inlet and outlet thereof, said secondary air and supplementary air serving to lean said initial mixture to provide for a substantially complete burning of the mixture in said combustion chamber, and means for supplying air at the outlet of the combustion chamber in sufficient volume to reduce the back pressures in the combustion chamber.

13. A heater including a preassembled air and fuel mixing unit having an inlet at one end and an outlet at its opposite end, electrical means for supplying air and fuel to said unit at said inlet, a perforated heat insulating plate extending over said outlet, an electrical heating element extending through said unit, said heating element having a portion thereof extending outwardly from said unit at said one end, thermostatic means including a pair of bi-metallic switches mounted on said extending portion and responsive to the temperature condition of said heating element, one of said switches being arranged to control the operation of said heating element and the other of said switches being arranged to control the operation of said electrical air and fuel supply means, and means for retaining said thermostatic means on said extending portion.

14. In a heating unit of internal combustion type, the combination of a combustion chamber having an inlet with an air and fuel mixing unit having one end in fluid flow communication with said inlet, said mixing unit having a rim portion at said one end extending into said combustion chamber inlet, ignition means in said combustion chamber at said one end of the mixing unit, means for supplying air and fuel to said mixing unit for burning in said combustion chamber, and means for supplying secondary air for burning in said combustion chamber, said secondary air being admitted into said combustion chamber from about said rim portion, with said rim portion retaining the secondary air away from the mixture leaving the mixing unit at said one end until after the ignition of said mixture by said ignition means.

15. In a heating unit of internal combustion type, the combination with a combustion chamber having an inlet of an air and fuel mixing unit having one end in fluid communication with said inlet, said one end having a longitudinally extending rim portion thereon, perforate heat insulating means extending across said mixing unit at said one end, ignition means in said combustion chamber at said inlet spaced from said insulating means in the direction of fluid flow in said combustion chamber, means for supplying air and fuel to said mixing unit for burning in said combustion chamber, and means for supplying supplementary air for burning in said combustion chamber from about said rim portion, with the mixture leaving said mixing unit at said one end being moved away from said insulating means by said supply and supplementary air so that said insulating means is out of the path of the flames in said combustion chamber.

16. In a heater of the internal combustion type having a combustion portion operating at substantially atmospheric pressure, the means for conditioning the heater fuel for combustion, said means including a walled portion in fluid-flow

communication at one end part with the combustion portion of the heater and having a fuel and air introducing portion at another part to introduce air and fuel adjacent one another into the walled portion, means for supplying heat to the walled portion to vaporize the fuel introduced therein and heat the air introduced therein, and apertured means at said one end part through which the mixture of vaporized fuel and heated air passes to the combustion portion.

17. In a heater of the internal combustion type in which combustion takes place at substantially atmospheric pressure, the combination including a combustion portion at substantially atmospheric pressure in which combustion is initiated at a position therein, means for conditioning the heater fuel for combustion, said means including a walled portion in fluid-flow communication at one end part with said combustion portion of the heater and having a fuel and air introducing portion at another part to introduce air and fuel adjacent one another into the walled portion, means for supplying heat to the walled portion to vaporize the fuel and heat the air introduced therein, and apertured means at said one end part through which the mixture of vaporized fuel and heated air passes to the combustion portion, and air ports for introducing air into the combustion portion beyond said position at which combustion is initiated to improve the combustion after said position.

18. In a heater of the internal combustion type, the combination including a combustion portion, an air supply portion separated therefrom, and means for conditioning the heater fuel for combustion including a walled portion having one end part extending into the combustion portion and in fluid-flow communication therewith and another part extending into the air supply portion to be cooled by the air in said supply portion, said conditioning means including a fuel and air introducing portion to introduce fuel and air into the walled portion, and means for supplying heat to the conditioning means to vaporize the fuel introduced into the walled portion and heat the air therein and provide a vaporous mixture thereof, with said vaporous mixture passing to the combustion portion for combustion.

50 19. A heater of the internal combustion type including in combination an enclosing housing, and heater structure within the housing including a combustion portion extending substantially longitudinally of the housing at one side thereof and having an inlet part at one end portion, an air supply portion extending along another side of said housing at said one end portion, including two air supplies with one of said air supplies being for passing over the outside of said combustion portion, and the other of said air supplies being in fluid-flow communication with the combustion portion, a fuel conditioning portion at said inlet part communicating with said combustion portion for receiving air from said other air supply and for receiving fuel, heating means for vaporizing the fuel within said conditioning portion for passage as a vaporous mixture into said combustion portion, and fuel supply means within said housing having a portion along a further side of said housing with said further side extending substantially longitudinally relative to said one side for the combustion portion, with said fuel supply means supplying fuel to the conditioning portion.

75 20. A heater of the internal combustion type

including in combination an enclosing housing, and heater structure within said housing including a combustion portion along one side of the housing and having an inlet part, an electrically operated fuel pump and fan driving means along another side of the housing extending substantially longitudinally relative to the combustion portion and adjacent thereto, fan means driven by said driving means and a pair of air supply portions exposed thereto extending along a further side of the housing substantially at right angles to the first two mentioned sides, a fuel conditioning portion at said inlet part to receive fuel from said fuel pump and air from one of said supply portions, means for vaporizing the fuel within the conditioning portion to provide a vaporous mixture with the air therein for said combustion portion, and with said other air supply portion supplying air over the outside of the combustion portion.

21. A heater system of the internal combustion type having operating structure assembled substantially in an L-shape, said structure including in one leg portion of the substantially L-shape a longitudinally extending combustion portion having an inlet at one end, an air circulating portion on the outside of said combustion portion longitudinally thereof, a pair of air supply portions at said one end of said combustion portion, with one of said air supply portions in fluid-flow communication with said air circulating portion, and the other air supply portion in fluid-flow communication with said combustion portion, fuel vaporizing means in said other air supply portion having a fuel and air inlet part and an outlet part communicating with said combustion portion inlet, with heating means for heating said vaporizing means to vaporize the fuel therein, air moving means having at least a portion thereof in the other leg portion of the substantially L-shape communicating with both air supply portions to supply air thereto for combustion and circulating purposes, and housing means enclosing said operating structure.

22. In a heater of the internal combustion type including a combustion portion, a combustion air supply portion separated therefrom but in fluid-flow communication therewith, and means for conditioning the heater fuel for combustion including a walled portion having an outlet part in fluid-flow communication with the combustion portion and another part exposed to the air in the air supply portion for cooling the walled portion at said another part, said walled portion having air and fuel supplied thereto, and means for supplying heat to the conditioning means to vaporize the fuel therein and heat the air and provide a vaporous mixture thereof, with said vaporous mixture passing to the combustion portion through said outlet part.

23. In a heater of the internal combustion type, a combustion chamber including a one-piece body originally provided in flat sheet form and formed to a chamber structure having a combustion portion extending longitudinally thereof and within the body, a plurality of fins spaced apart on the outside of said combustion portion and extending longitudinally and radially relative to the combustion portion, with each fin including a pair of oppositely disposed walls joined in an integral longitudinal edge at the outside thereof and being separable at the inside thereof, a plurality of combustion portion wall parts, each part being integral with one fin wall

from each of two adjacent fins to form a longitudinally extending wall for the combustion portion, and means dividing said combustion chamber into a plurality of passages including a partition wall having a portion on each of two sides extending within a corresponding fin at the inside thereof, said partition wall being retained in said body by contact with the walls of said corresponding fins.

10. 24. In a heater having a fuel supply and an air supply and a combustion portion with the latter operating at low pressure, the combination with means for conditioning the fuel for combustion of thermal operated means for controlling the fuel feed, said conditioning means including a walled portion for receiving fuel from the fuel supply and in fluid-flow communication at an outlet end with the combustion portion, heating means for heating the walled portion for vaporizing the fuel introduced therein, said heating means having a portion extending outwardly from the walled portion, and said thermal operated means including a portion movable responsive to the heat in the heating means and 25 acting upon movement to control the fuel feed to the walled portion.

25. A heat exchange unit including a one piece body member originally provided in flat sheet form and formed to a tubular structure having 30 a bore extending axially thereof, said body having the periphery thereof integrally formed with spaced longitudinally extending but laterally projecting fin portions, said fin portions being bent double with their inner ends opening into 35 said bore, and means dividing said bore into a plurality of longitudinal passages including a partition means having longitudinal side portions receivable within the inner ends of corresponding fin portions to retain said partition means in 40 said body member.

26. A heat exchange unit having a body member with a longitudinal bore extending therethrough, said body member being integrally formed with a plurality of spaced radial extensions, each of said extensions having opposite 45 wall portions joined at the outer end and open at the inner end thereof so that the space within a radial extension is open to said longitudinal bore, and partition means for defining a plurality of chambers in said body member having portions extending within certain of said radial extensions at the inner ends thereof, with the wall portions of said certain radial extensions retaining said partition means in said body member.

55. 27. A preassembled liquid fuel vaporizing unit for fluid flow therethrough including a tubular body member open at one end and substantially closed at the opposite end thereof, and having an inner stop portion spaced from said opposite end, a substantially cup-shaped member receivable within said body member through said one end thereof and having a perforated portion engageable with said stop portion to define an air and fuel mixing chamber within said unit at said opposite end, and a perforated wall portion positioned transversely of said body member intermediate said open end and said cup-shaped member, with said perforated wall portion and perforated portion defining an equalizing chamber substantially within the confines of said cup-shaped member, and heating means positioned longitudinally within said body member for heating the same.

60. 28. A preassembled liquid fuel vaporizing unit having a substantially closed end and an open

end for fluid flow from the substantially closed end to the open end, said unit including a tubular housing member having an air and fuel mixing chamber adjacent the substantially closed end and an equalizing chamber adjacent the open end therein, an insert of substantially cup-shape receivable within said housing member through the open end thereof, said insert having a perforated portion spaced from the substantially closed end of said housing member, with said 10 perforated portion and the substantially closed housing end defining said mixing chamber, perforated wall means intermediate the perforated portion of said insert and said open end extending transversely of said housing member, with 15 said wall means and perforated portion defining said equalizing chamber, and heating means extending longitudinally of said housing member for heating the same.

29. In a heater having an internal combustion portion with an inlet, the combination of means preparing a liquid fuel for burning including a first region with air and fuel being fed into said first region adjacent one another, an air supply to the first region for creating turbulence in the 25 fuel and air in the first region to mix them, a second region for the mixture wherein the turbulence is lessened and the mixture made substantially uniform throughout, and means acting on both regions for heating the fuel and air in said 30 both regions to condition the fuel and the mixture, said mixture passing at the inlet into said combustion portion to be ignited.

30. In a heater of the internal combustion type, the combination including a combustion 35

portion, a fuel conditioning portion opening into the combustion portion having fuel and air introduced therein adjacent one another, a region within the conditioning portion adjacent the 5 place of introduction, with the fuel and air being intermixed in said region substantially in a turbulent state, said conditioning portion having a region adjacent the outlet thereof to the combustion portion wherein the mixture is smoothed out and a rich mixture of fuel and air is obtained to pass into the combustion portion to be ignited, and means acting on both regions for heating the mixture in said both regions, and air inlets for introducing additional air into the combustion portion beyond the point of initial combustion and provide progressive combustion beyond said point.

31. In a heat generator of internal combustion type the combination of a plurality of portions including an air supply portion having air moving means therein, a combustion portion, and an air and fuel conditioning portion having one part in communication with the air supply portion and receiving air therefrom, with fuel introduced at said one part, and said air moving means providing for turbulence in the air and fuel to improve the mixing thereof, and said air and fuel conditioning portion having another part communicating with the combustion portion with mixing and conditioning being substantially completed therein, and means providing heat at said air and fuel condition portion to heat the air and vaporize the fuel in both parts therein.

HARRY B. HOLTHOUSE.
